UNITED STATES PATENT OFFICE.

WILLIAM H. ZINN, OF ANNISTON, ALABAMA.

KNOCKDOWN STROBOSCOPE.

1,214,636.

Specification of Letters Patent.

Patented Feb. 6, 1917.

Application filed January 10, 1916. Serial No. 71,238.

To all whom it may concern:

Be it known that I, WILLIAM H. ZINN, a citizen of the United States, residing at Anniston, in the county of Calhoun and State of Alabama, have invented a certain new and useful Knockdown Stroboscope, of which the following is a full, clear, and exact description.

My invention relates to stroboscopes, my special purpose being to give the various parts of the stroboscope such form as to enable them to be readily grouped and arranged for purposes of shipping and then quickly assembled for conjoint use in the complete device.

More particularly stated, I seek to produce a stroboscope adapted for general use and having a so-called knockdown construction whereby its various parts may be shipped or mailed in an ordinary envelop.

Reference is to be made to the accompanying drawings forming a part of this specification, and in which like reference characters indicate like parts throughout the several views.

Figure 1 is a perspective of the stroboscope complete. Fig. 2 is a substantially central vertical section through the same. Fig. 3 shows a blank made of cardboard or other sheet material, and which may be used in constructing the pedestal. Fig. 4 is a perspective of a block or plate used as a part of the bearing. Fig. 5 is a plan view of one of the visual strips carrying the stroboscopic images. Fig. 6 is a plan view of a card of sheet material provided with slots and adapted to be formed into the image cylinder. Fig. 7 is a plan view of a blank to be used as the bottom of the image cylinder. Fig. 8 is a top view, partly in plan and partly broken away, showing the base plate of the device.

A pedestal 9 is made of sheet material of any appropriate kind such, for instance, as thick cardboard. The pedestal has in this instance the proximate form of a pyramid, but this exact shape is not essential. A base plate 10 engages the lower end of the pedestal, which for this purpose is provided with a sunken portion 11, the outer portion of the base plate sloping upwardly to the top of the sunken portion, as may be understood more particularly from Fig. 2. In the construction of the pedestal I sometimes prefer to use the blank shown in Fig. 3 and having the general form of a Maltese cross. That is, a middle panel 9^a of square form is inte-

grally connected with four panels 9^b, each having its greatest width at its outer end. If desired, however, the panels 9^a and 9^b may be separate pieces, which are put together 60 and secured in any suitable manner. A block 12, made in this instance of wood, is secured to the panel 9^a, and forms a part of the pedestal. A pivot pin 13, which may be of any suitable material, extends upwardly 65 through the top of the pedestal. Any pivot pin will answer. A second block 14 carries a pivot cap 15 which fits loosely but neatly upon the upper end of the pivot pin 13. The block 14 is secured to a disk 16, through 70 which the pivot cap extends. The blocks 12 and 14 need not necessarily be made of wood. They may be plates or bits of thick pasteboard, cardboard or other appropriate sheet material.

The disk 16 is made of any suitable sheet material, and in this particular instance is of cardboard. It carries a number of tongues 17 each integral with it and extending radially outward from it. The disk 16 is 80 provided centrally with a hole 16^a through which the pivot cap 15 extends.

The image cylinder is shown at 18^a, and is provided with image slots 19. The image cylinder is made from a blank 18^a, having 85 the general form of a card, as shown in Fig. 6. This blank has a number of slots 19^a cut in it and adapted to serve, after the completion of the cylinder, as image slots 19. The blank 18^a is further provided with a 90 number of anchor slots 20, for receiving the tongues 17. The card 18^a and disk 16 are so formed and proportioned that the card may be bent around the edge of the disk, and thus brought substantially into cylindrical form, the tongues 17 being thrust through the anchor slots 20 and caused to protrude radially outward, as indicated in Fig. 1. The ends of the card being thus brought together, they are secured by any suitable means. While in this particular instance the image cylinder has a true cylindrical form, I do not limit myself thereby as it may be polygonal or have any other form which approximates that of a cylinder. 100

In Fig. 5 is shown an image band, carrying a number of separate but related images 22, 23, 24, 25, each representing a figure or scene differing from the others by graded changes in posture or position, somewhat after the manner of successive images upon a moving picture film. Each image band 110

has the form of a longitudinal strip or card, which may be bent into the form of a circle and disposed within the image cylinder. Any number of the image bands may be employed.

The operation of my device is as follows:—The several parts being made and assembled as above described, and a film band being placed within the image cylinder 10 as stated and as shown in Fig. 2, the operator turns the image cylinder. For this purpose he may gently strike one or more of the tongues 17 with his fingers, or he may simply spin the cylinder in any convenient 15 manner, as desired. Spectators now looking through the image slots at the images see the latter apparently in motion.

I invite special attention to the fact that the knockdown stroboscope constructed 20 as above described is well adapted for transportation. It may be sent through the mails, and if shipped by express or by freight it occupies a minimum of room. It is admirably 25 suitable for a mail order business, owing to the lightness with which the various parts may be made and the compact form in which they can be grouped together for transportation. The same envelop in which 30 the parts are shipped or otherwise transported may serve conveniently as a package for holding the parts after their transportation and when not in use.

I do not limit myself to the precise mechanism shown, as variations may be made therefrom without departing from the spirit 35 of my invention.

What I claim as new and desire to secure by Letters Patent is as follows:—

1. In a knockdown stroboscope the combination of an image cylinder provided with 40 image slots, and a pedestal for revolubly supporting said image cylinder; said pedestal being collapsible for purposes of shipment.

2. In a stroboscope, the combination of a 45 revoluble disk made of sheet material and provided with tongues extending radially outwardly therefrom, and a blank having 50 slots to engage said tongues and also having image slots, said blank being bendable so as 55 to form an image cylinder around said disk.

3. In a stroboscope the combination of a disk made of sheet material and provided with tongues extending radially outward and a blank having the general form of a 55 card and provided with openings for receiving said tongue in order to support said blank when the latter is bent substantially into the form of a cylinder, said blank being further provided with image slots and 60 with images and being normally flat so that said blank and said disk may be packed in compact form.

WILLIAM H. ZINN.
